Mason, ^{by} Bennett & Daerr and

United States Patent Office.

WILLIAM B. HAYDEN, OF COLUMBUS, OHIO.

Letters Patent No. 62,194, dated February 19, 1867.

IMPROVEMENT IN WIRE REIN SNAPS.

The Schedule referred to in these Letters Patent and making part of the same.

TO ALL WHOM IT MAY CONCERN:

Be it known that I, WILLIAM B. HAYDEN, of Columbus, Franklin county, State of Ohio, have invented a new and improved Rein Snap; and I do hereby declare that the following is a full, clear, and exact description thereof, reference being had to the accompanying drawings, making a part of this specification, in which—

Figure 1 is a side view of the rein snap.

Figure 2 is a top view of the same.

Figure 3 is a cross-section through red line $x-x$ in fig. 1.

Figure 4 is a perspective view of the rein snap of fig. 1.

Figure 5 is a modification of the rein snap of fig. 1.

Figures 6 and 7 represent perspective views of two metallic guards, such as are applied to the snaps of figs. 1 and 5.

This invention is designed to improve the strength and utility of rein snaps, which are formed of wire bent into shape, by applying to the shanks of such snaps a metallic guard so formed as to constitute a lateral stay for the spring-tongue, and also a means for confining the two wires forming the shank securely together, as will be hereinafter described.

To enable others skilled in the art to understand my invention, I will describe its construction and operation.

In the accompanying drawings, A represents a rein snap which is made of one piece of wire bent so as to form the eye a, the shank b, and the hook c, the point of which latter is where the two ends of the wire are brought together and welded. The spring-tongue d, which is used for closing the hook, is firmly secured at one end by a piece of metal, e, which passes around the shank b, and is firmly pressed by suitable machinery or tools.

My invention consists in applying to a rein snap, which is constructed as above explained, a metallic guard or shield, B, which may be made of sheet metal, of such form as will embrace the shank, b, of the snap, and extend therefrom alongside of the spring-tongue d, and thus serve as a means for supporting this tongue against lateral strain and displacement. In figs. 1, 2, 3, 4, and 6, the guard B is represented with its side supports connected together, so as to afford an additional support to the tongue d; but in figs. 5 and 7 this connection is omitted. The guard B is secured firmly to the shank b, by means of a suitable tool which will compress it snugly about the round wire, and thus increase the strength of the shank of snap at the same time. The guard B, shown in figs. 5 and 7, is made somewhat longer than that of fig. 1, so as to have it secured in place, in the act of applying the ring e to the shank, by means of this ring.

I am aware that it is not new to form guards upon malleable or other cast-metal rein snaps, and therefore I do not lay claim broadly to a guard or shield for supporting a spring-tongue of a snap, but shall confine my invention to a rein snap which is made of wire or wrought metal bent into proper shape. I have herein described and shown two modes of applying guards to the rein snap, and also two forms of guard; but I prefer to employ that form which is shown in figs. 1 and 6, as it covers the spring and strengthens it against an outward strain.

Having described my invention, what I claim as new, and desire to secure by Letters Patent, is—

The application of a guard or shield, B, to a rein snap which is made of wire, substantially in the manner and for the purposes described.

WM. B. HAYDEN.
